Inventor:

Max Rosenthal

By his Atty.
J. F. Regart

United States Patent Office.

MAX ROSENTHAL, OF PHILADELPHIA, PENNSYLVANIA.

Letters Patent No. 75,650, dated March 17, 1868.

IMPROVEMENT IN BUTTON-FASTENINGS.

The Schedule referred to in these Letters Patent and making part of the same.

TO ALL WHOM IT MAY CONCERN:

Be it known that I, MAX ROSENTHAL, of the city of Philadelphia, State of Pennsylvania, have invented a new and useful "Self-Fastening Button," that I style "Rosenthal's Self-Fastening Button;" and I do hereby declare the following to be an exact description thereof, reference being had to the accompanying drawings, and to the letters of reference marked thereon, making a part of this specification.

The nature of my invention consists in the fastening, attached to any kind or shaped button, and made of wire of any kind of metal, the wire being pointed at the outer end, and so bent as to form a loop or fastening to the cloth, as seen in the drawings, whilst the point is turned upwards toward the button, and inwards toward the centre, and on the outside of the cloth, between the button and the cloth, so that the eye or loop of the fastening is on the inside of the cloth, and the point on the outside, thus preventing the point from coming in contact with the flesh of the wearer, and forming a complete fastening, that is instantly fastened in the cloth by forcing the point through the cloth, turning the button once around, and by drawing the button outwards, the loop is firmly set and held in the cloth, so self-fastened as to require no sewing or bending of the wire afterwards to secure the button to the cloth, whilst the same button can be changed to be worn and used for years.

Figure 1 shows the button and pin.

Figure 2 shows how it is attached to the cloth.

I am aware that a screw-shaped wire-fastening has been used, but this I do not claim; but

What I claim as my invention, and desire to secure by Letters Patent, is—

A button-fastening formed of wire bent and shaped as shown and described, and having the pointed end of the spiral turned upwards for the purposes set forth.

MAX ROSENTHAL.
